AUXILIARY FUEL SUPPLY FOR AUTOMO-
BILE ENGINES

Charles J. Dempsey, Chicago, Ill.

Application December 30, 1935, Serial No. 56,836

4 Claims. (Cl. 158—46.5)

My invention relates to a mechanism for supplying fuel to automobile engines and is particularly directed toward improving the supply of fuel to the carburetor from the fuel pump which is used on the modern automobiles such for example as the Ford.

In the automobile using a fuel pump in lieu of the well known vacuum tank for supplying fuel to the carburetor, it is difficult to obtain a smooth flow of fuel to the carburetor that is most conducive to efficient operation of the motor.

The fuel pump together with the modern gasoline tank assembly, also creates certain new dangers of the motorist being left without an adequate supply of fuel without any warning to him. For example, if the fuel pump for any reason gets out of order or fails to function properly, the motorist is stranded even though he may have gasoline in the tank sufficient to take him to a repair station. Furthermore, the supply of gasoline available in the tank is in most instances measured by an indicating device mounted on the dashboard of the vehicle and such an indicating device may well be found out of order at a very inopportune time.

The present invention contemplates the provision of a simple device which gives the motorist relief from the above difficulties and dangers and provides in addition a simple means whereby the motorist may at his will test the mileage he is obtaining per gallon of fuel used.

Other objects and advantages of the invention will appear as the description proceeds in connection with the accompanying drawing wherein the preferred form of the invention is shown. It is to be understood however, that the drawing and description are illustrative only and are not to be taken as limiting the invention except insofar as it is limited by the claims.

In the drawing—

Fig. 1 is a plan view of a device assembled with a fuel pump and a carburetor on an automobile engine;

Fig. 2 is a view in side elevation of the auxiliary fuel tank;

Fig. 3 is a sectional view on the line 3—3 of Fig. 2; and

Fig. 4 is a view similar to Fig. 2 of a modification.

Referring now in detail to the drawing, in more recent models of pleasure automobiles as well as commercial vehicles, the well known vacuum tank is being replaced in many instances by a fuel pump. In the modern vehicle, there is little provision made for access to the gasoline supply tank for supplying the motor with fuel in the event of failure of the fuel pump for the supply line.

Furthermore, the supply of fuel from a fuel

pump is inherently of a pulsating character which is not conducive to the best operation of the carburetor.

In Fig. 1, the numeral 5 represents a fuel pump receiving fuel from a gasoline supply tank, not shown, through a conduit 6 and a valve 7. This pump is of course driven from the engine of the vehicle and pumps the fuel into a supply pipe 8. This supply pipe normally connects to a carburetor 9 at a fitting 10. The carburetor receives its air through an intake pipe 11 which is controlled by a butterfly valve 12 which is operated by shaft 13. The details of this structure are well known and need not be further described.

The present invention concerns itself with a simple device 14 which is interposed between the outlet line 8 from the pump and the fitting 10 leading to the carburetor 9. As stated hereinbefore, the functioning of the pump 5 or its failure to function smoothly, quickly upsets the smooth operation of the motor by failing to supply uniform flow of fuel to the carburetor 9.

The device 14 consists of an auxiliary tank which is so interposed in the fuel line from the pump 5 to the carburetor 9 as to operate as a cushioning means to even out the supply of fuel to the carburetor so that the pressure of the fuel supply to the carburetor and the flow thereof is more uniform and hence more effective in the operation of the motor. This device 14 comprises a tank or container which is substantially semi-cylindrical in shape as shown in Fig. 2.

On the flat side thereof, however, the slots 15 and 16 extend inwardly at an angle to a radius 35 of the cylinder of which the tank forms a part. Directly beneath the junction of the walls 15 and 16, I mount a fitting in a side wall 17 of the tank. This fitting is shown in cross section at 18 in Fig. 3 and is sealed tightly in the tank for example by soldering or brazing or welding. The fitting 18 is adapted to receive the free end 19 of the fuel conduit 8. This free end 19 has a ball portion 20 thereon, and a leak proof connection is obtained by means of a sleeve 21 which is rounded at 22 to fit on the ball 20 and which is screw threaded into the fitting 18.

The fitting 18 carries one end of a pipe 23 which pipe extends through the wall 24 of the tank 14 and is sealed thereto by soldering or other suitable means as indicated at 25. The side wall 24 is drawn twice, once to act as a snug sleeve for pipe 23, the other to act as a cup for solder. The free end of the pipe 23 carries a ball portion 26 adapted to be received in the fitting 10 which is like the fitting 18. A sleeve 27 screw threads into the fitting 10 to provide a leak tight joint as will be readily understood. The pipe 23 within the tank 14 has an opening 28 which in the normal operating position of the tank 14 faces 60

downwardly into the tank although the opening functions equally well if directed in any other direction.

The tank 14 also carries a combination vent and 5 drain or filler valve 29 which is mounted in the center of the semi-cylindrical surface 30 of the tank 14 and comprises a valve seat 31 fixed in the tank 14, a valve head 32 and vent openings 33 which are adapted when the valve is partly 10 opened to permit air to enter or escape from the interior of the tank 14.

Assuming that the tank 14 is in the fuel line 8 and is in its normal running position which is with the semicylindrical surface downward as shown in 15 Fig. 2 if the engine is started and the pump 5 is operated in the usual manner, fuel will be fed through the fuel line 8 and through the pipe 23 to the carburetor 9. Part of the fuel however, will be by-passed through the outlet opening 28 into the tank 14. The amount of fuel which is by-passed into the tank 14 is not sufficient to cause any difficulty in operating the motor even at the start when the tank 14 is 20 empty. In fact, there is a noticeable increase in 25 the smoothness of the operation in the engine immediately when this device is inserted in the fuel line.

Of course, after the engine has been running for a considerable length of time, the tank 14 becomes 30 practically filled with fuel, that is, the fuel is brought up to a level at least even with the outlet opening 28 and the further continued operation of the engine does not effect any particular 35 change in the container 14. The cushioning effect of the container 14 however remains effective at all times.

In the event of any failure of gasoline supply in the fuel tank or failure of the pump 5 to operate, the motorist may draw on the fuel supply in the tank 40 14. To do this, he simply lifts up the hood of his car and rotates the tank 14 in a clockwise direction as shown in Fig. 2 to bring it into the dotted line 45 position shown in this figure. He then loosens the vent valve 29 slightly to permit air to enter the tank 14. The frictional grip of the fittings 10 and 18 upon their respective ball portions 26 and 22 is sufficient to maintain the tank in the dotted line position. Therefore, so long as the supply of 50 gasoline in the little auxiliary tank 14 remains available, the motorist may operate his car and get to a repair station.

For purposes of testing the mileage of the car, the same procedure is followed except that in this case, the valve 7 may be turned off or the pump 55 may be stopped before starting the gasoline test and then the tank 14 is turned into the operating or dotted line position and the valve 29 is opened.

In the modified form of the invention shown in Fig. 4, the tank 14' is simply made of a different shape, that is, it is rectangular in cross section instead of semicircular.

In the event that the user of the machine desires to obtain a supply of gasoline for any purpose such as washing off the windshield, then it 65 is only necessary for him to open the valve 29 and he can obtain his gasoline without any difficulty. However, it is impossible for one stealing gasoline to obtain any more than the contents of the tank 14 until the engine is again started up.

70 From the above description, it is believed that the construction and advantages of this device will be readily apparent to those skilled in this art.

Having thus described my invention, what I claim as new and desire to secure by Letters Patent is:

1. In a fuel supply system for automobiles and the like, the combination with the carburetor, 5 and a fuel pump for supplying fuel to said carburetor of a fuel container interposed between fuel pump and the carburetor, a supply conduit from the fuel pump through the container to the carburetor, said conduit having an opening in the 10 side thereof within the container whereby to supply a portion of the fuel passing through it to the container and to impart the fluid pressure in the container to the fuel passing through said conduit to the carburetor, said container being 15 pivoted on said conduit whereby it may be inverted with respect to the conduit.

2. In a fuel supply system for automobiles and the like, the combination with the carburetor, and a fuel pump for supplying fuel to said carburetor 20 of a fuel container interposed between fuel pump and the carburetor, a supply conduit from the fuel pump through the container to the carburetor, said conduit having an opening in the side thereof within the container whereby to supply a portion of the fuel passing through it to the container and to impart the fluid pressure in the container to the fuel passing through said conduit to the carburetor, said container being substantially semi-cylindrical with said conduit as 30 the axis of the cylinder, and said container being adjustable about the conduit to position it above or below the conduit.

3. In a fuel supply system for automobiles and the like, the combination with the carburetor, 35 and a fuel pump for supplying fuel to said carburetor of a fuel container interposed between fuel pump and the carburetor, a supply conduit from the fuel pump through the container to the carburetor, said conduit having an opening in the 40 side thereof within the container whereby to supply a portion of the fuel passing through it to the container and to impart the fluid pressure in the container to the fuel passing through said conduit to the carburetor, said container being 45 adjustable about said conduit as a pivot to position the container above or below the conduit and a vent valve in said container at a remote point from the conduit for supplying air to the container when it is above the conduit. 50

4. In a fuel supply system for automobiles and the like, having a carburetor, a fuel pump for supplying fuel to the carburetor and a fuel conduit leading from the fuel pump to the carburetor, means to store a reserve fuel supply and to dampen the pulsations of fluid in said fuel conduit due to the pump action, said means comprising a conduit section inserted in said fuel conduit, a fuel tank with which said conduit section has permanent communication whereby the fuel may pass from the conduit section to the tank or from the tank to the conduit section at any time, said tank having a valve controlled vent opening therein whereby to close the tank for holding fuel therein or to vent the tank for discharging fuel therefrom, and means to hold the tank with the vent opening at the top and the communicating opening to said conduit section at the bottom thereof for draining the fuel tank contents into the fuel conduit. 70
